C. J. MEYER

MARINE PROPULSION DEVICE

Filed Oct. 12, 1921

BY

Erwin Wheeler & Woolard
ATTORNEYS.

UNITED STATES PATENT OFFICE.

CHRISTOPHER J. MEYER, OF MILWAUKEE, WISCONSIN, ASSIGNOR TO EVINRUDE MOTOR COMPANY, OF MILWAUKEE, WISCONSIN, A CORPORATION OF WISCONSIN.

MARINE PROPULSION DEVICE.

Application filed October 12, 1921. Serial No. 507,225.

To all whom it may concern:

Be it known that I, CHRISTOPHER J. MEYER, a citizen of the United States, residing at Milwaukee, county of Milwaukee, 5 and State of Wisconsin, have invented new and useful Improvements in Marine Propulsion Devices, of which the following is a specification.

This invention relates to improvements 10 in marine propulsion devices. More particularly this invention relates to the submerged gearing and gear case assembly of a portable marine motor of the general type disclosed in Letters Patent to Ole Evinrude, 15 Number 1,001,260, of August 22, 1911.

It is the object of this invention to provide a propeller shaft and bevel gear assembly wherein the thrust of the propeller is balanced against the thrust of the gears 20 which drive it. In the devices hitherto constructed the bevel gear carried by the propeller shaft has been mounted forward of the vertical transmission shaft from which it receives its power and the thrust bearing at the front end of the transmission shaft has been subjected to excessive wear 25 since it has had to withstand the combined thrust from the propeller and the meshed miter gears. In the construction herein- 30 after to be described, the gear carried by the propeller shaft is mounted at the rear of the vertical shaft and the thrust of the propeller tends to maintain the gears in mesh. The thrust bearing is therefore called upon to 35 absorb only the surplus of propeller thrust and the wear upon the shaft and bearing is reduced to a minimum.

It is a further object of this invention to provide a submerged gear casing wherein 40 the gears and the pump cam will be disposed in separate compartments. It is customary to operate the pump from a cam upon the propeller shaft thru the intermediation of an oscillatory plunger journaled in 45 the gear casing. Heretofore this cam has ordinarily been made integral with the miter gear by which the propeller shaft is driven and the plunger has reciprocated within the compartment containing the 50 gearing. In the improved construction of this invention the miter gear referred to is disposed at the rear of the casing and a partition wall separates the gear compartment from the compartment at the front

end of the casing which houses the pump 55 actuating cam and plunger. This forward compartment is provided with one or more ports thru which water is free to circulate responsive to the action of the plunger. In the old construction the gear chamber was 60 subjected to pressure pulsations due to the plunger action and it was consequently almost impossible to keep this chamber free of sand, grit, and water. In the construction of this invention the gear chamber may 65 be maintained at a constant pressure balancing the external pressure, whereby the water will neither tend to leak in, nor the oil tend to leak out. The cam chamber, on the other hand, being open to the free circulation of 70 water is freed from any possibility of sand accumulation therein.

A further object of this invention is to produce a gear casing which will effect the foregoing purposes and will nevertheless be 75 pleasingly symmetrical and be provided with graceful lines suggestive of speed.

Other objects are to devise means whereby the thrust bearing of the propeller shaft can be adjusted from the exterior of the 80 casing to take up wear, to provide said shaft with adequate line bearings, and to render the whole mechanism more readily accessible than has hitherto been the case.

The drawing represents the lower portions of a portable, or outboard motor, the casing in which the gears and pump actuating mechanism are housed being broken away to expose the interior construction.

The bracket 1 whereby the motor is secured to the transom of a boat is made fast to the sleeve 2 within which a rotatable sleeve 3 is supported. Sleeve 3 is secured at its lower end to the casing 4 which houses the bevel drive pinions and the pump actuating mechanism. This sleeve when released at its upper end turns upon its own axis due to the reaction of the propeller thrust thru the bevel drive pinions and allows the propeller to revolve to a reverse driving position in the manner disclosed in the patent to C. J. Meyer, Number 1,191,211, of July 18, 1916. Within the rotatable sleeve 3 is the vertically disposed power transmitting shaft 5 which is adapted to transmit to the propeller shaft 6 thru the submerged gear mechanism hereinafter to be described the power of the motor (not shown).

The casing 4 is substantially cylindrical in form with the exception of an integral collar portion 7 to which the sleeve 3 is made fast and a number of places where the exterior of the casing wall is thickened as at 8 to receive cap screws 9, whereby the cover plates 10 and 11 are secured in place to close the ends of the casing. These plates are preferably provided with annular flanges 11' 10 adapted to fit closely to the interior wall of casing 4 to prevent leakage.

Carried by the closure plate 10 is a tubular bearing member 15 within which the propeller shaft 6 is journaled. The hub 16 15 of propeller 17, which is adapted to receive the shaft 6, is provided at its forward end with a socket 18 of enlarged diameter within which is journaled the tubular bearing member 15. It will be noted that an extremely substantial mounting for the propeller is thus provided. The forward end of shaft 6 is journaled in a tubular bearing member 20 similar to member 15 previously described.

25 The upper side of bearing member 20 is cut away to make room for the mitered pinion 21 carried by the power shaft 5. A bevel gear 22 mounted upon propeller shaft 6 and in mesh with pinion 21 receives power therefrom. It will be noted that this arrangement gives the propeller shaft an unusual amount of support.

The pump mechanism includes a cylinder 25 adjustably supported from the fixed sleeve 2 by means of an adjustable clamping device 26. The pump plunger 27 is actuated by an annulus 28 which loosely encircles the sleeve 3 and is reciprocated by plunger 29 which moves in tube 30. A cam 40 31 upon the forward end of the propeller shaft imparts motion to the plunger 29 to actuate the pump plunger 27 in the manner aforesaid.

The tube 30 constitutes an integral extension of a cap member 32 which houses the cam and is secured to the gear casing 4 by the same bolts or cap screws 9 which retain the cover plate 11 in place. A port 33 is provided preferably in the bottom of cap member 32 to allow free access of the water to the interior of this member responsive to the reciprocatory motion of plunger 29. It is thereby made impossible for sand or other foreign matter to accumulate in the 55 compartment formed by cap member 32.

An adjustable thrust bearing member 35 is threaded into the end of the cap member 32 and some locking means, such as the set screw 36, is preferably provided to secure 60 any desired adjustment.

By reason of the fact that the pinion 22 is mounted rearwardly of the pinion 21, a left hand propeller 17 is used in place of the right hand propellers customarily found 65 upon this type of motor. The reversing ac-

tion, however, remains the same, the direction of rotation of sleeve 3 in reversing being clockwise as in previous models.

It will be noted that the propeller hub 16 is provided with a skirted portion 37 adapted to fit within a rearwardly extending flange 38 upon the rear closure plate 10. This construction taken with the cylindrical gear casing and the rounded cap which houses the pump actuating cam gives rise 75 to a smooth and unbroken external contour which is not only serviceable in making these parts pass readily thru the water with very little loss of power due to eddy currents, but also renders the device pleasing in its 80 appearance. The shape of the whole casing as determined by the cap piece, the gear housing and the skirted propeller is not perfectly stream lined but it is sufficiently so to be serviceably economical of power and 85 the long cylindrical outline with rounded ends is believed to be more attractive in outline than a perfectly stream line body.

The rudder fin 40, which is so shaped as to protect the propeller from injury, may be 90 cast integrally with the casing member 4 or may be attached thereto in any desired manner.

It will be obvious that the construction herein described and illustrated satisfies the 95 above specified objects and has other advantages over similar devices previously made.

I claim:

1. In a marine propulsion device provided with a substantially vertical power shaft and a sleeve concentric therewith, the combination of a casing supported from said sleeve and dirigible therewith, closures for the end of said casing provided with bearings, a shaft rotatably mounted in said bearings, power transmitting mechanism within said casing adapted to drive said last named shaft from said power shaft, a propeller upon the driven shaft, a cam upon the driven shaft exterior to the casing, a housing for said cam, and a plunger operatively associated with said cam within the housing, said housing being ported, whereby to relieve it of pressure.

2. In a marine propulsion device having a substantially vertical power shaft and a sleeve concentric therewith, the combination of a casing supported from said sleeve and dirigible therewith, closure plates adapted to seal the ends of said casing and provided with tubular journal members, a bevel gear upon the power shaft within the casing, a propeller shaft rotatably mounted within said journal members and extending beyond the casing at both ends, a bevel gear carried by said propeller shaft and meshing with said first named gear, a propeller upon one end of the propeller shaft and a cam upon the other end of said shaft exterior to said

casing, a protective housing enclosing said cam and the end of the propeller shaft upon which the cam is mounted, said housing being secured to said casing and provided with an aperture opening downwardly, and a plunger reciprocably mounted in said housing and adapted to receive motion from said cam.

3. In a marine propulsion device provided with a relatively fixed pump actuated by a plunger, and a dirigible propeller, propeller shaft and submerged driving connections therefor, the combination of a sealed casing surrounding said driving connections and provided with journals for said propeller shaft in its ends, a cam upon said propeller shaft exterior to said casing and operatively associated with said pump actuating plunger, and a housing ported in a lower portion for said cam and plunger separate from said casing.

4. The combination with a dirigible propeller, propeller shaft and driving connections therefor, of a casing provided with journal members at its ends adapted to receive said propeller shaft, a cam exterior to the casing upon the propeller shaft, a plunger operatively associated with the cam, and a ported housing separate from said casing enclosing the cam and plunger, whereby the cam and plunger will be protected from contact with obstacles and also from the accumulation of abrasive matter in said housing.

5. In a marine propulsion device provided with a substantially vertical power shaft and a sleeve concentric therewith, the combination of a submersible gear casing supported from said sleeve and provided with journals at its ends, a propeller shaft

rotatable in said journals, a propeller carried thereby, gears within said casing for driving said propeller shaft, a cam exterior to said casing and forward thereof, a housing for said cam supported from said casing, and an adjustable thrust bearing member carried by said housing and adapted to receive axial thrust upon said propeller shaft.

6. In a marine propeller device, a submersible gear casing provided with ported closures at its ends, tubular bearing members surrounding the ports in each closure, a propeller shaft rotatably mounted in said journal members and provided with a propeller at its end, a gear mounted upon said shaft within the casing and between said journal members, power connections for operatively driving said gear, a cam disposed forwardly of said casing upon the propeller shaft, a housing for said cam, and a thrust bearing for said propeller shaft mounted in said housing.

7. In a marine propulsion device provided with a vertically disposed power shaft and a sleeve concentric therewith, the combination of a casing supported from said sleeve, ported closures for the ends of said casing, a propeller shaft disposed within the ports of said closures and journaled therein, a drive gear carried by the power shaft, a driven gear mounted upon the propeller shaft rearwardly of said first named gear, a propeller at the rear end of said propeller shaft, a cam disposed forwardly of the casing on said propeller shaft, a housing for the cam separate from said casing, and a thrust bearing carried by said housing.

CHRISTOPHER J. MEYER.
